UNITED STATES PATENT OFFICE.

JOSEPH A. LEDOUX, OF WORCESTER, MASSACHUSETTS.

TOOL-HOLDER.

1,109,343.

Specification of Letters Patent.

Patented Sept. 1, 1914.

Application filed November 1, 1913. Serial No. 798,755.

To all whom it may concern:

Be it known that I, JOSEPH A. LEDOUX, a citizen of the United States, residing at Worcester, in the county of Worcester and 5 State of Massachusetts, have invented a new and useful Tool-Holder, of which the following is a specification.

This invention relates to a tool holder of the type designed for holding turning tools 10 in the tool-post of a lathe.

It is well known that a thin flat tool blade if properly supported may be used to accomplish work otherwise necessitating a heavy and expensive forged tool. Special devices 15 have heretofore been designed to facilitate the use of such flat blades for this purpose, and it is the object of the present invention to improve the construction of such devices, and to increase their efficiency while providing also for simplicity of parts and 20 economy of manufacture.

With this object in view my invention relates to certain devices, arrangements, and combinations of parts which will be hereinafter described and more particularly 25 pointed out in the appended claims.

A preferred form of my invention is shown in the drawings, in which—

Figure 1 is a side elevation of my improved tool-holder; Fig. 2 is a transverse sectional view taken along the line 2—2 in Fig. 1; Fig. 3 is a side elevation showing the parts of the tool holder separated; Fig. 4 is a sectional view taken along the line 4—4 in 35 Fig. 3 looking in the direction of the arrows; Fig. 5 is a top plan view of a modified form of my invention; Fig. 6 is a sectional view taken along the line 6—6 in Fig. 5; Fig. 7 is a side elevation of a second modification of my invention; and Fig. 8 is a 40 sectional view on the line 8—8 in Fig. 7.

The tool holder embodying my invention comprises essentially two parts, a body member 10 and a cap 11. These parts are shown 45 in Fig. 1 in their normal position resting upon the base of a tool post 12 and secured therein by the usual binding screw 13. A thin flat tool is indicated at 14, the tool in this case being formed from a worn out file, 50 such material having proved to be particularly adapted for use in my device. The body member 10 is cut away in its central portion to form a recess 15, and the ends of the body member are each provided with 55 undercut grooves 16 extending downwardly and rearwardly as clearly shown in Fig. 4.

The cap 11 is of such length as to fit within the recess 15 and is provided upon each end with a flange 17 disposed at an angle corresponding to that of the grooves 16 and adapted to slide therein. The body member 10 is also provided with a lateral projection 18 and the cap 11 has a flat upper portion provided with a depending flange 19. With this construction it will be seen that a tool 60 resting upon the projection 18 will be securely held thereon by the cap 11 and that pressure upon the cap, as by the screw 13, will force the cap and tool downwardly and rearwardly against the vertical face and lateral projection of the body member 10.

In the form of my device shown in Fig. 5 the tool clamping members are identical with those shown in Figs. 1 to 4, with the exception that the cap 11 is provided with a transverse slot 20 through which extends a clamping screw 21 threaded into the member 10. The body member is furthermore provided with a shank 22 angularly disposed with relation thereto and adapted to 70 be clamped within the tool post of a lathe. In this form of my invention the tool is held within the tool holder by the pressure exerted by the screw 21 while the tool holder itself is held within the tool post by the 75 shank 22. This form of holder is particularly adapted for close work upon large surfaces in cases where the lateral dimensions of the tool post would prevent the use of the ordinary holder.

The form of my invention shown in Figs. 7 and 8 is similar in its important features to those already described, but the body member 10 is provided with a supporting plate 23 which is freely movable transversely in ways 24 and 25 formed upon the under side of the member. The plate 23 extends laterally under the tool 14 and has upon its forward edge a flange 26. The rearward edge of the plate 23 is also provided with a flange 27 which is beveled upon its upper edge as indicated at 28. The cap 11 in this form of my invention is provided with a correspondingly beveled edge 29 and it will readily be seen that when the cap 11 is forced downwardly upon the tool 14 the beveled faces 28 and 29 will coöperate to force the supporting plate 23 rearwardly and thereby bind the lower edge of the tool firmly against the body of the holder.

Having thus described my invention it will be evident that other modifications and

changes therein may be readily made by those skilled in the art without departing from the spirit and scope of my invention as set forth in the claims annexed, and I do not wish to be limited to the details herein described, but

What I do claim is:—

1. As an article of manufacture, a tool holder comprising a body member and a cap, said body having integral upwardly extending ends with downwardly and rearwardly inclined grooves in their inner faces, and said cap having flanges in its ends corresponding to the angle of the grooves and adapted to slide therein.
2. As an article of manufacture, a tool holder comprising a body member and a cap, said cap being mounted to slide in diagonal ways in said body portion and having a transverse slot formed therein, and said body member having a clamping screw threaded therein and extending through the slot to secure the cap and the tool to the body member, said body member also having a shank projecting angularly from one end thereof to support the tool holder rigidly in a tool post.
3. As an article of manufacture, a tool

holder comprising a body member and a cap, said cap being mounted to slide diagonally in the body member and having an upwardly beveled rear edge, and said member being provided with a supporting plate mounted in transverse ways in its lower surface, said plate having a tool holding flange on the front edge and a beveled vertical flange on the rear edge, the beveled edge of the cap coöperating with the beveled flange to force the supporting plate rearwardly to clamp the tool.

4. As an article of manufacture, a tool holder comprising a body member and a cap, said body member having a supporting plate mounted in transverse ways in its lower surface, said plate and said cap having coöperating beveled surfaces so disposed that downward movement of the cap will cause rearward movement of the plate to clamp the plate to the body member.

In testimony whereof I have hereunto set my hand, in the presence of two subscribing witnesses.

JOSEPH A. LEDOUX.
